Primary Examiner — George D. Kirschbaum*Assistant Examiner* — Antoinette Martine Suiter(74) *Attorney, Agent, or Firm* — Sand, Sebolt & Wernow Co., LPA(57) **CLAIM**

The ornamental design for a woodworking square, as shown and described.

DESCRIPTION

FIG. 1 is a front, top, right side isometric perspective view of a woodworking square in accordance with our design; FIG. 2 is a rear, top, left side isometric perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a cross sectional view of the woodworking square taken along the line 9-9 of FIG. 7.

1 Claim, 7 Drawing Sheets(56)
